UNITED STATES PATENT OFFICE.

CHARLES F. WARRICK, OF DETROIT, MICHIGAN, ASSIGNOR TO PENBERTHY INJECTOR COMPANY, OF DETROIT, MICHIGAN, A CORPORATION OF MICHIGAN.

OIL BURNER.

Application filed October 8, 1924. Serial No. 741,980.

The invention relates to oil burners of the centrifugal type and consists in certain novel features of construction which are herein-after more fully described.

One of the objects of the invention is to provide a safety device for automatically cutting off the oil supply to the burner head in case the latter fails to rotate for any reason. For this purpose I have provided the centrifugal nozzle with a cup-shaped reservoir normally receiving the oil distributed to the burner and provided with an overflow conduit at the inner periphery thereof adapted to drain away any surplus oil collecting in the reservoir. When the nozzle is rotating normally the centrifugal force acting upon the oil in the reservoir throws the same outwardly towards the outer peripheral wall thereby preventing the accumulation of a sufficient supply to drain off through the drain conduit. If, however, the nozzle ceases to rotate the oil will immediately collect in the nozzle until the level rises to the opening of the drain conduit. Suitable means are also provided for collecting the oil from the drain conduit and actuating a shut-off valve for the oil supply.

Another object of the invention is to provide an improved atomizing nozzle having means for distributing the oil in a very thin film whereby it will leave the burner in a finely atomized condition. For this purpose I provide a nozzle with a cup portion having substantially cylindrical walls and a flaring portion having a conical surface connecting with the cylindrical walls.

Other objects will be more apparent after considering the detailed description herein-after given in connection with the accompanying drawings wherein:

Figure 1 is a sectional view of the improved oil burner;

Figure 2 is a transverse section on the line 2-2 of Figure 1;

Figure 3 is a diagrammatic view showing the burner in elevation and an apparatus for shutting off the fuel line by collecting the overflow oil from the burner.

The burner comprises an annular supporting base 1 having a laterally extending projection 2 adapted to support at the outer end an electric motor 3. 4 is the main housing suitably supported upon the base 1 and provided with the laterally extending hous-

ing 5, in axial alignment with the motor 3. Within the main housing there is a central stationary standard 6 having an oil passageway 7 therethrough adapted to carry the oil from the inlet opening 8 in the lower part of the housing to a distributing head 9 at the upper end of the standard, this head being provided with the radial passages 10. 11 is a sleeve or hollow shaft surrounding the standard 6 and rotatably mounted by the bearings 12 in the housing 4. This sleeve is driven by the bevel pinion 13 meshing with the bevel gear 14, the latter being mounted on a transverse shaft 15 which is rotatably mounted by the bearings 16 in the housing 5. The shaft 15 is connected to the motor 3 by an intermediate shaft 17 and suitable coupling connections 18.

The upper end of the main housing 4 is provided with an annular pan 19, while above the same is located a burner pan 20 having inner cylindrical walls 21. The nozzle 22 is secured to the rotatable sleeve 11 and extends upward through the burner pan 20 and is provided with suitable vanes 23 for directing the air supply adjacent the discharge point of the nozzle.

The nozzle comprises a cylindrical portion 24 surrounding the oil distributing head 9 and terminating at its upper end in the flaring annular wall 25 having a conical surface 26. The nozzle is also provided with an inner cylindrical wall 27 spaced from the cylindrical outer wall 24 and forming an annular recess 28 therebetween adapted to receive and collect the oil from the burner head. 29 is a tubular member inwardly spaced from the inner wall 27 and rising above the same to a point adjacent the distributing head 9. This member forms the annular discharge conduit 30 for any surplus oil rising above the top of the inner wall 27. Oil which collects in the conduit 30 passes by gravity into the annular pocket 31 from whence it is directed through the discharge passageway 32 in the downwardly extending flange 33 of the nozzle, this flange preferably extending into the annular pan 19 and forming a cover for the upper portion of the main housing 4.

With the construction as thus far described the oil which rises through the stationary standard 6 is distributed radially through the distributing head 9 into the cylindrical portion 24 of the rotating nozzle.

The nozzle is rotated by means of the electric motor 3 and the centrifugal force therefore distributes the oil along the cylindrical surface 24 into a thin film, the centrifugal force being sufficient to cause the film to flow upward against the action of gravity until it reaches the flaring portion 25 of the nozzle. At this point the film of oil is distributed outward to the periphery of the flange where it is thrown outwardly in a finely atomized condition. The air is delivered by means of the rotating vanes 23 to the under side of the oil spray, thereby forming a combustible mixture adapted to be completely burned.

If for any reason the burner ceases to be rotated, such as the breakage of the driving parts, the oil will no longer be distributed upward in the cylindrical portion of the nozzle and will collect in the annular pocket 28 and as soon as the level reaches the top of the inner wall 27 the oil will overflow through the annular discharge conduit 30 and the passages 33 collecting in the stationary oil pan 19.

In Figure 3 I have represented a method for shutting off the oil supply whenever the centrifugal force does not deliver the same from the nozzle, this comprising a drain pipe 34 leading from the stationary annular pan 19 to a bucket 35. The latter is normally held by a spring 36 in its upper position but is adapted to move to lower position when a predetermined amount of oil is collected therein. The movement of the bucket may be arranged in any suitable manner to close the valve 37 in the supply conduit 38, such for example, as by providing a lever 39 fulcrumed at a fixed support 40 and secured to the lower end of the spring 36, the outer end of the lever being connected to the rod 41 attached to the valve 37. It will be understood of course, that this is merely a diagrammatic illustration of an automatic shut-off connection since apparatus of this character is old in the art.

The burner is also provided with means for draining unburned oil from the furnace into the annular oil pan 19 so that in case the atomizing nozzle should feed oil with the burner unlighted the shut-off valve will be operated to cut off the oil supply to the burner. For this purpose the walls of the fire pot 44 are inclined so that the oil striking the same will drain into the annular burner pan 20, the latter being preferably filled with fire clay as indicated at 45. The inner wall of the burner pan is provided with an aperture 46 communicating with a vertical drain passageway 47 which, in turn is arranged directly above the oil pan 19. Thus, any oil which drains off the walls 44 will overflow through the aperture 46 and passageway 47 and will collect in the oil pan 19 where it will operate the automatic shut

off connection in the same manner as previously described.

What I claim as my invention is:—

1. In an oil burner, the combination of a rotary atomizing nozzle having an annular recess, means for delivering oil into said recess, a member spaced radially inward from said nozzle to form an annular conduit contained within and extending downwardly from said nozzle permitting a gravity discharge of oil accumulated above a predetermined level in said recess, the centrifugal force of the rotating nozzle normally preventing accumulation of the oil to said predetermined level in said recess. 75

2. In an oil burner, a rotary atomizing nozzle comprising spaced inner and outer walls forming an annular recess therebetween, a conduit communicating with said recess, a collecting chamber connected with said conduit, said rotary nozzle producing centrifugal force, thereby preventing the oil from reaching said conduit when said nozzle is rotating and gravitational force permitting the same when said nozzle is stationary. 80

3. In an oil burner, the combination with a stationary supply pipe and a rotatable sleeve surrounding the same, of a centrifugal nozzle carried by said sleeve comprising a cup having an outer distributing wall and an inner wall forming an annular receiving chamber between said outer and inner walls, a tubular member spaced from said inner wall to form an oil passage way and extending above the same, and a flange extending outwardly 100 from said cup provided with a discharge passage communicating with said oil passageway. 95

4. In an oil burner, the combination of a housing, an annular oil pan secured thereto, a stationary vertical conduit within said housing, an oil distributing head thereon, a rotatable sleeve surrounding said conduit, a cup-shaped nozzle secured to said sleeve having an outer wall, an inner wall and an annular baffle therebetween, the space between the inner wall and the baffle forming a gravity discharge conduit for oil above the level of said baffle, and a flange secured to said outer wall forming a covering for said housing, said flange being provided with an oil passage connecting with said discharge conduit and said oil pan. 110

5. In an oil burner, an oil head having a downwardly projecting portion at its outer edge, a rotary nozzle having an outer wall and an upwardly extending inner wall at its lower end, a tubular member spaced from said inner wall forming an overflow passage, said outer edge of said oil head projecting below the upper end of said inner wall of said nozzle between said outer and inner walls, thereby preventing the oil from flowing directly from the oil head into said overflow passage. 120

6. In an oil burner, the combination with
an oil distributing head, of a rotary cup
shaped nozzle surrounding said head having
a vertical outer wall, an outwardly extending
5 wall at the upper end, and an upwardly ex-
tending inner wall at the lower end thereof
forming an annular recess, a cylindrical
sleeve spaced within said inner wall and
extending vertically to said oil distributing
10 head, forming with said inner wall an an-
nular conduit adapted to convey surplus oil
from said nozzle.
7. In an oil burner, the combination with
an oil distributing head, of a rotary nozzle
15 surrounding said head having a vertical
outer cylindrical wall provided with an an-
nular pocket in the lower end adapted to
prevent the accumulation of an excessive
amount of oil, an annular conduit connect-
20 ing with said annular pocket adapted to con-
vey surplus oil from said nozzle, and a flange
at the upper end of said nozzle having a
conical surface connecting with the upper
end of said cylindrical wall.
- 25 8. In an oil burner, a rotatable atomizing
nozzle provided with an outer wall, an an-
nular baffle wall inwardly spaced from said
outer wall forming an annular oil receiving
30 recess therebetween, a sleeve concentrically
arranged within said nozzle providing an an-
nular conduit between said sleeve and baffle
wall, a member carried by the lower portion
of said nozzle provided with a downwardly
extending conduit in communication with
said annular conduit, and a reservoir posi-
tioned beneath said downwardly extending
35 conduit, centrifugal force upon the oil in
said annular recess preventing discharge of
oil through said conduits during rotation of
said nozzle.
9. In an oil burner, a rotatable atomizing
nozzle and means for supplying oil thereto,
said nozzle having an outer wall and at its
lower end an inner wall forming an annular
recess therebetween, a sleeve extending up-
40 wardly within said nozzle concentrically
therewith providing an annular conduit be-
tween said sleeve and said inner wall, said
conduit being in communication with said
nozzle above said inner wall, a downwardly
flaring hood carried by the lower portion of
45 said nozzle provided with a downwardly ex-
tending conduit in communication with said
annular conduit, a reservoir positioned be-
neath said hood adapted to receive surplus
oil from the nozzle when the latter fails to
50 rotate, the centrifugal force of said rotatable
nozzle preventing oil from entering said an-
nular conduit during rotation of the nozzle.
- In testimony whereof I affix my signature.

CHAS. F. WARRICK.
